Primary Examiner — Messina L Smith*Assistant Examiner* — Carolyn W Davis(57) **CLAIM**

The ornamental design for a shower set, as shown and described.

DESCRIPTION

FIG. 1 is a front, top and right-side perspective view of the shower set showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a rear, bottom and left-side perspective view thereof;

FIG. 9 is an enlarged view, of circled portion 9, of FIG. 1, thereof;

FIG. 10 is an enlarged view, of circled portion 10, of FIG. 1, thereof; and,

FIG. 11 is an enlarged view, of circled portion 11, of FIG. 8, thereof.

The broken lines throughout the drawing figures depict portions of the shower set that form no part of the claimed design.

The dot-dash broken lines encircling portions of the shower set indicate enlargement boundaries and form no part of the claimed design.
